UNITED STATES PATENT OFFICE

1,972,801

TOBACCO CAN

Percy J. Shelton, Chagrin Falls, Ohio

Application December 5, 1933, Serial No. 701,034

4 Claims. (Cl. 206—56)

The present invention relates generally to cans and more particularly to tobacco cans and has for its prime object to provide means in a can of this nature whereby the contents of the can 5 may be maintained at a convenient level for ready accessibility as may be required by the smoker.

Another very important object of the invention resides in the provision of a tobacco can of this nature which is simple in its construction, compact and convenient in its arrangement of parts, 10 comparatively inexpensive to manufacture, easy to manipulate, thoroughly efficient and reliable in use and otherwise well adapted to the purpose for which it is designed.

With the above and numerous other objects in view as will appear as the description proceeds, the invention consists in certain novel features of construction, and in the combination and arrangement of parts as will be hereinafter more 15 fully described and claimed.

In the drawings:

Figure 1 is a sectional elevation showing a can embodying the features of my invention.

Figure 2 is a horizontal section taken substantially on the line 2—2 of Figure 1.

Figure 3 is a horizontal section taken substantially on the line 3—3 of Figure 1.

Figure 4 is a perspective view of one side of the can.

Figure 5 is a perspective view of a stop clip.

Figure 6 is a vertical section through another embodiment of the invention.

Figure 7 is a perspective view of the forward tray used with this embodiment.

Figure 8 is a perspective view of one side of this embodiment.

Figure 9 is a vertical sectional view through a third embodiment of the invention.

Figure 10 is a horizontal section taken substantially on the line 10—10 of Figure 9, and

Figure 11 is an elevation of the rod.

Referring to the drawings in detail and first particularly to the embodiment of the invention shown in Figures 1 to 5 inclusive it will be seen that the numeral 5 denotes the body of the can which is provided on one side with a vertical slot 6 starting from a point spaced from the bottom and extending through the upper edge thereof. L-shaped tongues 7 project from the edges of the slot 6 adjacent the upper edge of the can which extend outwardly from the can and then outwardly from each other. A follower tray 9 is slidably mounted in the can and from its sides are struck tongues 10 inwardly bent to engage the paper tobacco container usually used in cans of

this nature. The back wall of the follower tray is provided with a projection 11 extending through the slot 6 and on opposite sides of an opening therein being provided with threads to engage threaded sides of a rod 12. A housing 14 is fixed 60 to the slotted side of the can body 5 and in this housing moves the projection 11 and is located the rod 12. The rod 12 projects through an opening in the top of this housing. This rod 12 is provided with a pair of threaded sides oppositely disposed and a pair of plane sides oppositely disposed. Thus the rod may be lifted when engaged with the projection 11 to lift the follower tray and the contents of the can upwardly to the desired point and then the rod may be turned and released from the 70 projection 11 and slid down until it engages the bottom of the housing 14 and then turned again into engaging position with the projection 11 thereby holding the follower tray in the raised 75 position.

A clip 16 closes the upper end of the slot 6 and has tongues 17 to engage with tongues 7 and intermediate its ends is bent over the upper edge of the can as clearly shown in Figure 1.

Now referring to the embodiment of the invention shown in Figures 6 to 8 inclusive it will be seen that the body 5a has the slot 6a. The tray 9a is slidable in the body 5a and is provided with the tongues 10a and has a projection 11a extending through the slot 6a which is adapted to be 85 manually moved for lifting the tray 9a.

Referring now to the third embodiment of the invention shown in Figures 9, 10 and 11 it will be seen that the can body 5b is not provided with a slot as in the first and second embodiments 90 described. A tray 9b is slidable in this can body and has a portion of its back wall bent forwardly and inwardly of the can to provide a hollow projection 11b with which cooperates a rod 12b in the same manner as was described in the first 95 embodiment of the invention. This rod 12b is located inside the can being slideable through a bearing 20 provided in the upper portion of the can. The bottom of the follower tray 9b has an opening 21 through which the bottom of the 100 rod may project to rest on the bottom of the can body 5b.

It is thought that the construction, operation and advantages of this invention will now be quite apparent to those skilled in this art without 105 a more detailed description thereof.

The present embodiments of the invention have been described merely by way of examples since in actual practice they attain the features of advantage enumerated as desirable in the 110

statement of the invention and the above description. It is to be understood that numerous changes in the details of construction, and in the combination and arrangement of parts may be resorted to without departing from the spirit or scope of the invention as hereinafter claimed or sacrificing any of its advantages.

Having thus described my invention, what I claim as new is:

- 10 1. In combination, a can, a follower tray in the can, one side of the can being provided with a slot, a projection on the tray extending through said slot, a housing on said side of the can, a rod slidable and rotatable in said housing and projecting through an opening in the upper end thereof, and detachably engageable with the projection.
- 20 2. In combination, a can, a follower tray in the can, one side of the can being provided with a slot, a projection on the tray extending through said slot, a housing on said side of the can, a rod slidable and rotatable in said housing and projecting through an opening in the upper end thereof, and detachably engageable with the projection, by means of being provided with two opposed plain sides and two opposite threaded sides, said projection having an opening therein through which the rod passes, said opening being provided with opposed threaded portions with

30

which the threaded portions of the rod are engageable.

3. In combination, a can, a follower tray in the can, a projection carried by the tray and having an opening therein, the walls of which are formed with opposed threaded portions, a shaft, means for rotatably and slidably supporting the shaft from the can, said shaft passing through the opening in the projection and said shaft being provided with two opposed plain sides and two opposite threaded sides, the threads of said two sides engaging the threaded portions of the opening in the projection when the shaft is in one position and said threaded parts of the shaft being opposite the plain sides of the opening when the shaft is in another position.

4. In combination, a can, a follower tray in the can of less length than the length of the bottom of the can and said tray including a bottom part and side walls and one end wall, said side walls and said end wall contacting portions of the sides and one edge wall of the can, a container in the can for containing the contents thereof, a portion of the bottom part of the container resting on the tray, tongues punched inwardly from the vertical walls of the tray for engaging the container, and means for manually adjusting the tray in the can.

PERCY J. SHELTON.
